TUBING CALIPER**Arthur H. Brandon, 1450 Ramillo Ave.,
Long Beach 15, Calif.****Filed Apr. 3, 1958, Ser. No. 726,152****1 Claim. (Cl. 33—178)**

This invention relates to improvements in tubing calipers primarily designed for the purpose of determining whether walls of tubing in a well have corroded or have been worn and to what extent.

A primary object of the present invention is to provide an improved tubing caliper having a plurality of radially arranged fingers swingably mounted on a central supporting structure and urged outwardly into engagement with the walls of a tubing, and to provide an improved construction for transmitting the movements of the feeler fingers so that the extent to which the tubing walls have corroded or worn away can be accurately ascertained.

Another object of the invention is to provide a tubing caliper wherein a simple but highly efficient means is provided for pivotally mounting the feeler fingers and their movement transmitting bellcranks or levers on the central supporting structure.

Another object of the invention is to provide a novel, simple mechanism for electrically transmitting in an intelligible manner the movements of the feeler fingers to the surface, and to provide a construction by which the same can be very accurately adjusted.

With the foregoing and other objects in view, which will be made manifest in the following detailed description and specifically pointed out in the appended claim, reference is had to the accompanying drawings for an illustrative embodiment of the invention, wherein:

Figure 1 is a sectional view through a tubing illustrating the central portion of the tubing caliper embodying the present invention as disposed therein;

Fig. 2A is a sectional view through the upper portion of the part of the apparatus illustrated in Fig. 1, illustrating the apparatus in that position assumed when the fingers are in an unworn or uncorroded portion of tubing as illustrated in Fig. 2B;

Fig. 2B is a sectional view of the lower portion of that part of the apparatus illustrated in Fig. 1;

Fig. 3A and Fig. 3B are views similar to Figs. 2A and 2B, respectively, but illustrating the apparatus in that position assumed when one or more of the feeler fingers have encountered a recess in the tubing wall that may have been occasioned either by corrosion or tubing wear;

Figs. 4 and 5 are horizontal sections, respectively, taken upon the lines 4—4 and 5—5 in Fig. 2B in the direction indicated; and

Fig. 6 is a wiring diagram.

Referring to the accompanying drawings wherein similar reference characters designate similar parts throughout, the improved tubing caliper comprises a central bar or mandrel 10 adapted to be lowered such as by a conductor cable in a tubing T that is to be tested. At the top and bottom of that portion of the apparatus illustrated in Fig. 1, there are centralizing belly springs, not shown, which frictionally engage the walls of the tubing T and tend to hold the mandrel 10 centered with respect to the tubing. These belly springs engage the walls of the tubing with insufficient friction to make the

2

device self-supporting in the tubing. That is, even though the belly springs frictionally engage the walls of the tubing and hold the mandrel centralized with respect to it they do not prevent the tool from descending under its own weight or being withdrawn from the tubing by the conductor cable when the conductor cable is elevated.

On the mandrel 10 there is mounted a sleeve or collar 11 that is fastened in position such as by a set screw 12. This collar has a plurality of radially arranged slots 13 formed in the exterior surface thereof which are defined from each other by what might be regarded as radial ribs 14.

A problem exists in a tool of this character as to how to pivotally mount as large a number of feeler fingers as is possible, it being desirable to employ a maximum number of feeler fingers so that as much of the interior surface of the tubing T will be traversed thereby as possible. In accordance with the present invention, a groove 15 is formed in the top of the collar so as to traverse the tops of the ribs 14. The feeler fingers 16 are positioned in the slots 13 and pivot pins 17, one for each feeler finger, are positioned in the groove 15. The pivot pins 17 are confined in the groove 15 by means of a cap 18 which is tightened down against the top of the collar 11 such as by screws 19. The cap is provided with radially extending ribs that are in alignment with the ribs 14 and which define therebetween slots that, in effect, form continuations of the slots 13. In this manner, a multiplicity of feeler fingers 16 can be mounted in radial arrangement on the collar 11 in close proximity to each other.

The feeler fingers have knobs 20 formed thereon adjacent their lower ends which engage the interior wall surface of the tubing T. These knobs preferably are hard-faced at their extremities so as to resist wear. The feeler fingers are urged outwardly by means of springs 21, the upper portions of which are hooked as at 22 against the backs or inner edges of the feeler fingers. The other ends of the springs 21 are inserted in aligned apertures 23 in a sleeve 24 that is positioned on the mandrel 10 against the underside of the collar 11. These ends of the springs, after being positioned in the aligned apertures, are fastened in position by peening the metal with a center punch or the equivalent as indicated at 25. This construction merely serves to constantly urge the lower ends of the feeler fingers outwardly into engagement with the interior of the tubing T.

When a tubing caliper engages a corroded or worn spot on the interior of a tubing, one or more of the feeler fingers are permitted to swing outwardly. The magnitude of the movement of the feeler finger however is quite small and one of the problems involved in the limited space permitted in a tubing caliper is to transmit this movement with a minimum amount of effort so that intelligible information can be obtained at the surface as to just how far the feeler finger has expanded and whether the tubing section being tested has become dangerously weak.

Above the cap 18 a sleeve 26 is positioned on mandrel 10 and serves to support a plate 27 which has radial slots in its outer edge. A sleeve 28 rests on the plate and has a radially slotted flange 29 at its bottom in which there is formed a groove 30. The groove 30 receives a split ring 31 which serves in turn to pivotally support a plurality of bellcranks or levers 32. The ring 31 is confined in the groove 30 by the plate 27. The lower ends of the bellcranks 32 are disposed closely adjacent the upper ends of the feeler fingers and are adjustably engaged thereby, the adjustment being provided by bolts 33 which are threaded through the tops of the feeler fingers and which actually engage the bellcranks. These bolts when adjusted are locked in adjusted position such as by

jam nuts 34. The tops of the bellcranks extend outwardly and downwardly to engage the downwardly and inwardly inclined surface 35 on an internal flange formed at the bottom of a skirt 36 that surrounds the mandrel. The skirt has a hub portion 37 which is slidable upon the sleeve 28. It is constantly urged upwardly by tension springs 38 anchored at their upper ends on bolts 39 and at their lower ends in studs 40 that are threaded into the top of the skirt so that adjustment of the tension exerted by the springs can be accomplished. On the top of the skirt 36 there is a stud 41 to which is threaded a collar 42. A push rod 43 is fastened in the top of the collar 42 such as by a set screw 44. This push rod serves to vertically move a contact member generally indicated at 45. The contact member 45 has a plurality of contacts thereon, indicated respectively by the reference characters 46, 47, 48, 49, and 50 which are separated from each other by insulation 51. These contacts are electrically connected to each other and to ground as illustrated in Fig. 6. Adjacent the contact member, blocks of insulation 52 are mounted on the skirt and contacts in the form of screws 53 are mounted on the arms 54 of pivotally mounted contact supports. The contact supports are pivoted for swinging movement about pivots 55 and are continually urged toward the contact member 45 by leaf springs 56. They are so arranged with respect to the contacts 46, 47, 48, 49, and 50 as to sequentially engage their respective contacts when the contact member is moved vertically. Thus, as illustrated in Fig. 2A, the lowermost contact screw 53 is barely in engagement with its contact 46. The next contact screw 53 has not engaged but is almost in engagement with its contact 47. The third contact screw 53 is spaced a greater distance from its contact 48. Similarly, the fourth contact screw 53 is spaced somewhat farther from its contact 49 and the uppermost contact screw 53 is spaced considerably from its contact 50. If the contactor 45 is moved downwardly the second contact screw 53 will be brought into contact with its contact 47 and subsequently the third contact screw will be brought into contact with its contact 48. Thereafter, the upper contact screws will be brought into contact with their contacts 49 and 50 in sequence.

It will be noted that the contact screws 53 are longitudinally adjustable with respect to the arms 54 merely by rotating and screwing the contact screws in their respective arms. As the arms 54 swing about the axes of pivots 55 which are normal or at right angles to the axis of the contact member 45 a considerable adjustment or screwing of the screws 53 is possible before the adjustment causes any appreciable change in the vertical position of its contacting end with respect to the dividing line between its contact of the contact member and the insulation 51 thereon. This arrangement makes a very fine adjustment possible in that if it is found that the contacting end of the contact screw 53 should be raised or lowered slightly to preserve the desired sequence of operation a considerable screwing of the contact screw can be done to perform this adjustment and the vertical change in position is very small. Consequently, the parts can be very accurately adjusted to have the proper sequence of operation brought about by the outward swinging movement or expansion of a feeler finger 16.

The lowermost contact screw 53 has a resistor 57 in series therewith, and is connected to the next contact screw and to a resistor 58 associated therewith. This resistor, in turn, is connected to the third contact screw 53 and to the resistor 59 associated therewith which, in turn, is connected to the fourth contact screw and the resistor 60 associated therewith. The fourth contact screw is connected to the uppermost contact screw 53 and to the conductor cable, not shown, which, in turn, is connected to a source of current represented by battery 61 and to a meter or recording device indicated at 62 which, in turn, is grounded as indicated at 63.

In testing tubing the apparatus as above described is

caused to vertically pass through the tube. When a pit or depression indicated at P on Fig. 3B is encountered by one or more of the feeler fingers 16, these feeler fingers will be urged outwardly by means of their springs 21. 5 When the feeler fingers are swung outwardly the adjusting the adjusting screws 33 thereon force the lower ends of their bellcranks 32 inwardly causing the outer ends of the bellcranks to move downwardly on the inclined surface 35 and in effect cam the skirt 36 downwardly against the 10 action of the tension springs 38. The relationship of the bellcranks to the inclined surface is such that a very small amount of outward swinging movement of the feeler fingers 16 is translated into vertical movement of the skirt which, in turn, moves the contact member 45 15 downwardly. The extent of downward movement of the contact member is dependent upon the extent of outward swinging movement of one or more feeler fingers 16. If the outward swinging movement is relatively small it may be that only the lower contacts 46 and 47 will be engaged 20 by their respective contact screws 53. If this is the case, current from the source of supply 61 is required to pass through both resistors 59 and 60 before reaching ground. Consequently, a relatively small reading will be obtained upon the meter or recorder 62. On the other hand, if the 25 outward swinging movement of the feeler finger 16 is of considerable magnitude the downward movement of the contact member 45 will be greater, and if contacts 46, 47, 48, and 49 are all engaged by their contact screws 53, the current need only pass through resistor 60 before 30 reaching ground, and the reading on the meter will be correspondingly greater. When the uppermost contact 50 is engaged by its contact screw a direct current through the contact member to ground is provided with the result that the meter reading is the maximum. In this 35 manner, even though the space available in the caliper is very small, five different depths to which the feeler fingers 16 may be expanded can be accurately determined. Additional contacts may be arranged on the contact member 45 and additional contact screws can be associated 40 with them respectively if desired.

In some instances, the apparatus above described, can be run in two sections which are duplicates of each other and which are run in tandem between the belly springs. If this is the case, the feeler fingers of one section are 45 preferably oriented or arranged in straddling relationship to the feeler fingers of the other section. In this manner, the entire inside surface of the tubing can be calibrated.

It will be appreciated from the above-described construction that the feeler fingers and their bellcranks can 50 be easily and efficiently mounted for pivotal or swinging movement on the central supporting structure, and that small movements of the feeler fingers can be translated into movements of the contact member 45. Furthermore, the degree of extent of movement of the contact member 55 can be accurately ascertained by the number of resistances 57 to 60, inclusive, that are cut in or shunted out of the electric circuit.

Various changes may be made in the details of construction without departing from the spirit and scope of 60 the invention as defined by the appended claims, wherein:

I claim:

A tubing caliper comprising a central supporting structure, a plurality of feeler fingers swingably mounted upon 65 said supporting structure and urged outwardly with relation thereto to engage the interior of a tubing, bellcranks pivotally mounted on the supporting structure, one for each feeler finger, a skirt axially movable on the supporting structure, and disposed in surrounding relation to the bellcranks, the skirt presenting a downwardly and inwardly inclined surface engageable by one end of each bellcrank, means forming an adjustable engagement between each bellcrank and its respective finger whereby 70 when any feeler finger is allowed to swing outwardly its bellcrank will cause the skirt to move axially, and means 75

for indicating the distance that the skirt has moved in response to a feeler finger swinging outwardly.
